DESIGN FOR A VELOCIPED

Harold L. van Doren and John G. Rideout, Toledo,
Ohio, assignors to The American-National
Company, Toledo, Ohio, a corporation of Ohio

Application April 27, 1935, Serial No. 56,607

Term of patent 7 years

To all whom it may concern:

Be it known that we, Harold L. van Doren and John G. Rideout, both citizens of the United States of America, residing at Toledo, in the county of Lucas, in the State of Ohio, have invented a new, original, and ornamental Design for a Velocipede, of which the following is a specification, reference being had therein to the accompanying drawing, forming a part thereof, wherein:

Figures 1, 2, and 3, respectively, are perspective views taken from different angles of a velocipede showing our new design.

We claim:

The ornamental design for a velocipede substantially as shown.

HAROLD L. VAN DOREN.
JOHN G. RIDEOUT.
